COIN SELECTOR

Louis Steiner, Belle Harbor, N. Y.

Application April 1, 1948, Serial No. 18,443

5 Claims. (Cl. 194—102)

1

This invention relates to coin selectors of a type suitable for use in connection with coin-controlled mechanisms, and more particularly to a coin selector adapted to detect and entrap coins which are of improper size or are underweight, as well as those containing ferromagnetic material.

An important object of the invention is to provide in a coin selector of this kind an improved means for dislodging and ejecting from the selector counterfeit or imperfect coins which have been arrested therein.

Another object of the invention is to provide in a coin selector of this character an improved coin discharge gate arranged for co-action with said coin dislodging means.

A further object of the invention is to provide in combination with said discharge gate a means for forcing moving coins against a coin gauge whereby undersize coins may be accurately detected and the movement thereof arrested.

Still another object of my invention is to provide in combination with the aforesaid discharge gate a movable magnetic means arranged to be retracted from a position in contact with said gate upon the opening of the latter whereby an area within the coin selector will be demagnetized and ferromagnetic coins arrested within said area may fall therefrom.

A further object of my invention is to provide in a coin selector having a coin gauge for detecting undersize coins means for causing coins to approach said gauge at uniform speeds.

Other objects and advantages of the invention will be apparent from the following description of a preferred embodiment thereof, taken in connection with the accompanying drawings, in which:

Fig. 1 is a front elevational view of a coin selector embodying my invention, certain of the parts being cut away for clearness of illustration;

Fig. 2 is a rear elevational view of the same;

Fig. 3 is a sectional view taken substantially on the line 3—3 in Fig. 1;

Fig. 4 is a sectional view similar to that shown in Fig. 3 but illustrating the parts of the coin selector in position to eject an arrested coin;

Fig. 5 is a sectional view of the coin selector taken on the line 5—5 in Fig. 1;

Fig. 6 is a similar view taken on the line 6—6 in Fig. 1;

Fig. 7 is a front elevational view of the coin selector with parts removed to bring out the structural details of a plate which may form the body of the device;

2

Fig. 7-a is an end view taken from the right of Fig. 7;

Fig. 8 is an enlarged fragmentary elevational view of a trap portion of the plate shown in Fig. 7;

Fig. 9 is a fragmentary end view taken from the right of Fig. 8;

Fig. 10 is an enlarged fragmentary elevational view of a portion of the plate illustrated in Fig. 7 bringing out the details of a pivot pin supporting means;

Fig. 11 is a fragmentary end view taken from the right of Fig. 10;

Fig. 12 is an enlarged fragmentary elevational view of another portion of the plate shown in Fig. 7 showing means for supporting a magnet holder comprising a part of the coin selector;

Fig. 13 is a fragmentary end view taken from the right of Fig. 12; and

Fig. 14 is a detailed view of a bearing pin adapted to be received by the plate shown in Fig. 7 for supporting a pivot pin upon which a coin discharge gate is mounted.

Referring in detail to the drawings, the numeral 15 designates a supporting plate which, in the present embodiment of the invention, serves as an integral part of my coin selector. Said plate may be of an irregular outline having an upper right-hand side edge 16 (as viewed in Fig. 1) and lower right-hand side edges 17 and 18, the latter of which may extend to the lower portion of the plate upon which may be provided suitable means (not shown) for mounting the plate in a coin controlled vending machine, for example. The plate may be defined on its left-hand side (again as viewed in Fig. 1) by edges 19, 20 and 21 and at its top by a top edge 22 on which may be formed an offset portion 23 adjacent the edge 16.

Upon the front side 24 of the support plate 15 tortuous coin passages 25, 26 and 27 may be formed by spaced ribs integral with the plate, the forward side of said passages being closed by a cover 15a which may be attached to the support plate as by screws 15b. Said passages may communicate at their lower ends with any desired coin operated mechanism (not shown), as, for example, a coin operated release mechanism of the type for freeing a vending machine for operation when suitable coins have been received. The upper ends of the passages communicate, respectively, with vertically disposed coin passages 28a, 29a and 30a which may be formed integrally with the plate 15 (Fig. 7) and in turn communicate, respectively, with diagonally disposed coin

passages 28, 29 and 30 which have open ends adjacent the edge 16 for receiving coins.

The passage 28 is defined along a portion of its upper side by a rib 31 which is disposed along the edge portion 23 of the plate 15 and has upon its lower end a boss 32 which has an edge 33 formed transversely of the rib and extending into the passage. A rib 34 extends from the boss 32 diagonally downwardly toward the edge 21 of the plate 15, said rib 34 being parallel to the upper edge 22 of the plate and being disposed in offset relation to the rib 31. The rib 34 has formed on its lower side a projecting edge portion 35 which extends into the passage 28, and both the rib and the boss 32 have formed therein a longitudinal notch 36 which extends parallel to the upper edge 22 of the plate 15. Spaced slots 37, 38, 39 and 40 disposed transversely of the rib 34 are formed in the plate 15.

The lower edge of the passage 28 is defined by a diagonal rib 41 which is disposed parallel to the rib 34 and provided with an upwardly extending portion 42 adjacent the edge 16 of the plate 15.

The lower end of the rib 41 is disposed in spaced relation to the edge 21 of the plate 15 at the upper end of the interconnecting coin passage 28a.

Formed on said edge 21 is a rib 44 which defines the outer edge of the coin passage 28a and which is provided with an arcuate inner edge 45 disposed opposite the lower end of the rib 41. An arcuate slot 46 is formed in the plate between the lower end of the rib 41 and the arcuate inner edge 45 of the rib 44.

A rectangular opening 47 is provided in the plate 15 in the upper portion of the coin passage 28 below the projecting edge portion 35 of the rib 34. A portion of the plate below the opening is formed to provide a beveled wall section 48 which extends above the rib 41 to the lower edge of the opening 47. The wall section 48 has a lower edge 49 which is slightly above the rib 41, and extends parallel to the latter. The dimensions of the beveled wall section 48 and the opening 47, when the passage 28 is of a proper size for receiving a U. S. quarter, for example, may be such as to accommodate a coin smaller than a genuine quarter resting in a tilted position against the wall section 48 with its lower edge on the rib 41 and with its upper portion extending into the opening 47. When said passage 28 is adapted to receive U. S. quarters, the space between the upper edge of the rib 41 and the edge 50 of the opening 47 is slightly less than the diameter of a genuine quarter and the space between the rib 41 and the lower surface of the projecting edge portion 35 of the rib 34 is slightly greater than the diameter of a genuine quarter.

Holes 51 extending through the plate 15 transversely of the notched portion 36 of the rib 34 are disposed adjacent the slots 37, 38, 39 and 40, and formed upon the uppermost edge 22 of the plate 15 adjacent the edge 21 an offset with respect thereto is an integral bracket 52 on the face of which is provided a longitudinal notch 53 disposed parallel to the notch 36 in the rib 34.

The coin passage 29 may be adapted to receive dimes introduced therein at the edge 16 and is defined along its lower edge by the upper edge of a rib 54 which, like the ribs 34, 41 and 44, may be formed integral with the face of the plate 15. The rib 54 is parallel to the rib 41 and may be spaced therefrom a distance sufficient to permit a dime to roll down the former. The rib 41 includes a downwardly projecting boss 32 similar to that on the rib 31, and said boss may also

have an edge 33 extending transversely of the rib and into the passage 29. The rib 41 is provided with a longitudinal notch 58 which is intersected by slots 59 and 60 disposed adjacent the ends of the notch, and holes 61 corresponding to the holes 51 are provided adjacent the slots. Extending downwardly from the lower end of the rib 41 is a rib 62 formed with an arcuate inner edge 63 which is disposed opposite the lower end of the rib 54, and another arcuate slot 46 is formed in the plate 15 between the lower end of the rib 54 and the arcuate inner edge 63 of the rib 62.

A rectangular opening 65 is provided in the plate 15 in the upper portion of the coin passage 29 below the projecting edge portion 35 of the rib 41. A portion of the plate below the opening 65 is formed to provide a beveled wall section 66 defined by a lower edge 67 which is spaced slightly above the upper edge of the rib 54 and extends parallel thereto. The upper edge of the opening 65 is disposed slightly below the projection 35 and is parallel to the latter. The dimensions of the beveled wall 66 and the opening 25 65 may be such as to accommodate an undersize dime resting in a leaning or tilted position against the wall section 66 with its lower edge on the rib 54 and with the upper portion of the coin extending into the opening 65.

A rectangular slot 68 aligned with the opening 65 is provided in the plate 15, said slot being disposed in the notched portion 58 above the projection 35 of the rib 41. The wall adjacent the lower edge of the slot 68 includes a tapered portion 68b (Fig. 3) extending from the edge of the slot to the rear surface of the plate 15.

The coin passage 30 may be of a size suitable for receiving nickels introduced into the same adjacent the edge 16 and is defined by the lower edge of the rib 54 and by a rib 69 parallel thereto. The rib 54 is similar to the rib 41 and includes a boss 32, an edge 33, and a projection 35. The rib 54 is also provided with a longitudinal notch 58, slots 59 and 60 and holes 61. Extending downwardly from the lower end of the rib 54 is a rib 62a which is formed with an arcuate inner edge 63a. The spaced ribs 62 and 62a define the aforesaid coin passage 29a which interconnects the lower end of the coin passage 29 and the upper end of the coin passage 26. A third arcuate slot 46 is formed in the plate 15 between the lower end of the rib 69 and the arcuate inner edge 63a of the rib 62a. Said coin passage 30 is provided with a rectangular opening 65a, a beveled wall section 66a, and a slot 68a which are similar to the corresponding parts in the passage 29, except that the dimensions of the beveled wall section 66a and the opening 65a are such as to accommodate, for example, an undersized U. S. nickel resting in a leaning position against the beveled wall with its lower edge on the rib 69 and its upper portion extending into the opening 65a.

The forward side of the coin passage 28 is normally closed by a cover plate 70 (Figs. 1 and 3). Said plate 70 is of a configuration generally conforming to the shape of the side of the coin passage 28 and is provided with a downwardly extending portion 70a which is adapted to cover the interconnecting coin passage 28a. An upper edge 71 at one side of the plate 70 registers with the upper edge 22 of the plate 15 and a centrally disposed rectangular projecting portion 72 of the plate 70 extends upwardly above the upper edge of the plate 15. The plate 70 has provided thereon, in alignment with its edge 71, a plurality

of spaced apertured ears 72a which extend transversely of the plate and are adapted to be received in the slots 37, 38, 39 and 40 in the plate 15 with the apertures in the ears 72a in alignment with the notch 36 in the rib 34. Means are provided for pivotally mounting the plate 70 on the plate 15 and to this end, there are provided pins 73 (Fig. 14) formed with transverse bearing openings 73a at one end and screw threads at the other end. The pins 73 are adjustably mounted in the holes 51, as by nuts 74 (Fig. 2), with the bearing openings 73a disposed in alignment with the notch 36 in rib 34. A pivot pin 75 (Figs. 1 and 5) is journaled in the bearing openings 73a in the pin 73 and the apertured ears 72a of the plate 70 are pivotally supported thereby to provide a pivotal mount for the plate 70. Said pivot pin is longitudinally disposed in the notch 36 in the rib 34 and may be adjusted therein by adjusting the position of the pins 73 by turning the nuts 74. The rib 34 is provided with a longitudinal beveled edge 34a (Figs. 3 and 13) which extends from the notch 36 to the edge 22 of the plate 15. This beveled edge 34a accommodates the upper edge 71 of the plate 70, when the latter is pivoted outwardly from the coin passage 28 about the pivot pin 75, and acts as a stop for limiting the extent of the pivoted movement of the plate (Fig. 3).

The plate 70 has provided therein a rectangular opening 76 disposed opposite to and in overlapping relation with the opening 47 and the tapered wall section 48 on the plate 15 (Fig. 1). A thin tilting plate 77 is pivotally mounted on the plate 70 by a pin 78 which is journaled on grooved bosses 79 disposed on either side of the lower portion of the opening 76 (Figs. 1 and 4). The plate 77 has a diagonal upper edge 80 which is disposed in a manner such that the upper end of the plate projects through the opening 76 in the plate 70, across the passage 28, and into the opening 47 in the plate 15 for a purpose hereinafter appearing.

The uppermost portion 72 of the plate 70 has formed thereon a transversely disposed longitudinal flange 81 extending over the uppermost edge 22 of the plate 15. Extending upwardly from the flange 81 are an apertured ear 82 (Fig. 1) and two pairs of ears 83 and 84, the latter of which are formed with aligned, transverse apertures.

The forward side of the coin passage 29 is normally closed by a plate 85 similar to the plate 70 and comprising a downwardly extending portion 86 which ordinarily covers the interconnecting coin passage 29a. The upper edge of the plate 85 is defined by an edge portion 87 (Fig. 1) which has formed thereon transversely disposed apertured ears 88 received in the slots 59 and 60 in the plate 15. The apertures in ears 88 are aligned with the longitudinal notch 58 in the rib 41 and a pivot pin 89, for pivotally supporting the plate 85, is disposed in the notch 58, passed through the apertured ears 88 of the plate 85, and journaled at each of its ends in apertured pins 73 which are disposed in the holes 61 in the plate 15 and adjustably secured by nuts 74 as in the manner previously described.

The plate 85 is also provided with a transversely disposed flange 90 which extends from the upper edge thereof and projects through the slot 68 in the plate 15 (Fig. 3).

The rib 41 is provided with a groove 41a which extends upwardly from the notch 58 (as shown in Fig. 11) and accommodates the upper edge 87 of

the plate 85 on each side of the flange 90 when said plate 85 is pivoted outwardly from the coin passage 29 about the pivot pin 89. The surface of the groove thus acts as a stop for limiting the movement of the pivoted plate. The plate 85 is provided with a rectangular opening 76, similar to the corresponding opening 76 in the plate 70, and is disposed opposite to and in overlapping relation with the opening 65 in the plate 15. A thin tilting plate 77, similar in all respects to the corresponding plate on the plate 70, is pivotally mounted adjacent the opening 76 in the plate 85 and is adapted to be pivoted so as to project through said opening, across the passage 29, and into the opening 65 in the plate 15.

The coin passage 30 and the interconnecting coin passage 30a are normally covered by a pivoted plate 93 which is similar in all essential details to the plate 85 and includes a transversely disposed flange 93a which extends through the slot 68a in the plate 15 and a small pivoted plate corresponding to the plates 77 on the cover plates 70 and 85.

A magnet holder, indicated generally by the numeral 95, is pivotally mounted on the bracket 52 and comprises a channel-shaped member 96 having apertured ear portions 97 extending transversely of its upper end. The member 96 is mounted on a pivot pin 98 which is received by ears 97 and journaled in the notch 53 of the bracket 52. The pin 98 may be retained in said notch as by a cover plate 99 spanning the notch and screwed to the bracket (Fig. 6). The channel member 96 comprises a wall portion 100 and flange portions 101 adapted to ride on the outer surface of the plate 70 as shown in Fig. 6. A magnet 102 is attached to the inner surface of the wall 100 and a pair of horizontally spaced magnetizable steel pins 103 are fitted in appropriate transverse openings therefor in the plate 70. Each of the pins 103 is disposed opposite one of the poles of magnet 102 and it will thus be understood that when the poles of the magnet 102 are in contact with the pins 103 in the plate 70, a magnetic zone is created in the coin passage 28 between the plate 70 and the plate 15.

The plate 70 has fixed thereon, adjacent its lower edge, an offset bracket 104, similar to the member 95, which extends downwardly to a position overlapping a portion of the upper part of the plate 85. The bracket 104 has attached to its inner surface a magnet 102 similar to that previously described, and the plate 85 is provided with a pair of steel pins 103 which are disposed therein opposite the poles of the latter magnet 102. The plate 85 is, in turn, provided with a bracket 104a which is adapted to overlap an upper portion of the plate 93 and support a magnet 102 in a position opposite steel pins 103 also provided in the plate 93. It is thus apparent that the magnets 102 create magnetic zones in the lower ends of the coin passages 28, 29 and 30 when said magnets are in contact with the pins 103, and it follows that the magnetic effect is broken upon the pivoted movement of the plates 70, 85 and 93, which cause the member 95 and the brackets 104 and 104a, respectively to move outwardly from the next lower plate and thus effect a separation of the magnets 102 from their respective magnetizable steel pins 103.

For ejecting undersize or oversize coins trapped in the coin passage 28, a pusher member, indicated generally by the numeral 105, is mounted on the flange 81 on the upper portion 72 of the plate 70. The member 105 comprises a wall 106

(Fig. 2), attached by screws or otherwise fixed to the flange 81, and a downwardly extending wall 107 disposed to the rear of the plate 15 and substantially parallel thereto. On the lower end of the wall 107 is formed a downwardly and inwardly extending portion 108, the lowermost end of which is disposed opposite the opening 47 in plate 15, as shown in Fig. 3. Said lower end of the portion 108 supports the upper end of the pivoted tilting plate 77 which extends through the opening 76 of the cover plate 70, across the passage 28, and into the opening 47 in the plate 15.

Another pusher member, indicated generally by the numeral 109, is secured to the flange 90 on the upper edge of cover plate 85 and comprises a wall 110 upon which is provided an upstanding apertured lug 111 (Fig. 4). The member 109 further includes a vertical wall portion 112, extending downwardly from the wall 110, from which extends a wall 113 parallel to wall 110 and directed toward the plate 15 (Fig. 3). An outwardly projecting lug 112a is provided on the wall 112, and from the wall 113 there extends downwardly and inwardly an inclined portion 114, the lowermost end of which is disposed opposite the opening 65 in the plate 15. The lower end of the portion 114 is adapted to support the upper edge of the pivoted tilting plate 77 which, as above explained, extends through the opening 76 in the cover plate 85, across the passage 29, and into the opening 65 in the plate 15. The cover plate 93 is also provided with a pusher member, shown generally at 109a, which is similar in all respects to the member 109 previously described, and is mounted on the flange 90a of the cover plate 93. This latter pusher member has a lower end disposed opposite the opening 65a in plate 15 and supports the uppermost end of the plate 77 which is pivotally mounted upon the cover plate 93 and extends through the opening 76 therein into the opening 65a of the plate 15.

For imparting pivotal movement to the cover plate 70 a diagonally disposed link 119 may be provided to the rear of the plate 15, one end of the link being pivotally engaged in the aperture in the ear 82 formed on the flange 81 on the uppermost edge of the plate 70 (Fig. 2). It will readily be understood that when the link is pulled downwardly the plate 70 will be pivoted outwardly from the coin passage 28 about the pivot pin 75 as is best shown in Fig. 4, the slanted surface 34a at the upper edge of the plate 15 serving to limit the extent of the pivotal movement. Any suitable means may be provided for imparting downward movement to the link 119 and the specific means used for this purpose may depend upon the installation with which my coin selector is employed. For example, if the coin selector is employed in a position above a coin changer or a coin operated release mechanism in a merchandise vending machine, the link 119 may be operatively connected with the mechanism for operating the coin changer or release mechanism, as the case may be. In other installations the link 119 may be operatively connected to a suitable hand-operated slide or lever.

A pin 120 is mounted substantially horizontally in the pairs of apertured ears 83 and 84 on the upper portion 72 of the cover plate 70 and a link 121, having an offset portion 122 at its upper end (Fig. 5), is pivotally mounted upon said pin. The lower end of the link 121 is pivotally connected to the lug 111 on the pusher member 109 by a pivot screw 123 and it will thus be understood

that the pivoting movement of the cover plate 70 produced by downward movement of the link 119 will be transmitted to the cover plate 85 through the link 121 and the member 109. A coil tension spring 124, secured at one end to the upper edge 22 of the plate 15 and at its other end to the lug 112a on the pusher member 109, is adapted to return the cover plates 70 and 85 from pivoted positions to their normal positions, closing the sides of coin passages 28 and 29, respectively. This action may be made more positive by the use of a supplementary coil tension spring 125 secured at one end to a suitable bracket mounted on the upper edge 22 of the plate 15 and at its other end to a lug portion 126a on the link 121 (Fig. 4).

A link 121a pivotally interconnects the pin 120 and the lug 111 on the pusher member 109a mounted on the cover plate 93 in order that the latter plate will be pivoted to an open position simultaneously with the plates 70 and 85. Coil tension springs 124a and 125a may extend from the pusher member 109a to the upper edge of the plate 15, in a manner similar to the springs 125 and 124a, for retracting the cover plate 93 to its normal position after having been pivoted.

For detecting underweight simulated coins which pass through the coin passages 28, 29 and 30, balancing levers 126 are mounted upon the rear side of the plate 15, on pivot pins 127, at points corresponding to the centers of curvature of the arcuate slots 46, respectively. The levers 126 may be secured on the pivot pins as by cotter pins 128, and the levers 126 may each comprise an arm 129 having a transversely disposed lug 130 at the outer end thereof. The lugs 130 extend through the arcuate slots 46 in the plate 15 and are thus disposed transversely within the short interconnecting coin passages 28a, 29a and 30a. Weights 131 are mounted on the extremity of another arm 132 of the lever 126, said weights on the individual balancing levers being selected so as to counterbalance a simulated coin or object falling onto the lug 130 provided said simulated coin or object has a weight less than that of a genuine coin. A genuine coin on the other hand will be heavy enough to counterbalance the weight, thereby rotating a lever 126 in a clockwise direction, as viewed in Fig. 4, and permitting the coin to pass downwardly into the communicating coin passage 25, 26 or 27, as the case may be.

In the operation of my coin selector, coins may be inserted into the coin passages 28, 29 and 30 at the open ends thereof adjacent the upper side edge 16 of the plate 15. A genuine quarter, for example, inserted into the passage 29 will roll down the same, pass beneath the projection 35 and move past the opening 47 and in so doing will tilt the pivoted plate 77 out of the passage by making contact with the diagonal edge 80 of said plate. The quarter will then be received on the balancing means 126 and, being of the proper weight, will rotate the lever arm 129 to permit the coin to fall through the passage 28a into the communicating coin passage 25. If the inserted coin is of a diameter greater than that of a genuine quarter, the coin will be stopped by the projection 35 inasmuch as the space between the projection 35 and the rib 41 is but slightly greater than the diameter of a genuine coin. The forward edge of the arrested oversize coin will be disposed partially over the opening 47 and, by pulling the link 119 downwardly the cover plate 70 will be pivoted outwardly from the coin passage 28, simultaneously causing the pusher mem-

ber 105 to enter the opening 47, dislodge the coin from its arrested position in the passage and cause it to fall vertically along the outside of the coin selector. The rejected coin may be returned to a customer, for example, by means of appropriate chutes or the like (not shown).

If the coin inserted into the passage 28 is undersize, it will roll down the passage on the upper edge of the rib 41 until it reaches the opening 47. Because the diameter of the undersize coin is of a measurement less than the space between the rib 41 and the upper edge 50 of the opening 47, the presence of the tilting plate 77 in the passage will force the coin toward the beveled wall portion 48 immediately below the opening 47. It will be understood that the undersize coin will be thus arrested in the opening 47 in an inclined position against the wall portion 48. Upon pulling the link 119 downwardly, the plate 70 will be pivoted outwardly uncovering the coin passage 28 and simultaneously causing the pusher member 105 to move through the opening 47 into contact with the undersize coin to eject the same from its arrested position in the same manner as previously described with regard to an oversize coin.

If the inserted coin is of normal size but underweight, the coin will move along the upper edge of rib 41, displace the tilting plate 77, and roll past the opening 47 to the lower end of coin passage 28. Upon reaching the balancing means 126, the coin will come to rest on the lug 130 thereof. Because the coin is underweight, it will not rotate the lever and will be retained on the lug 130 until the cover plate 70 is pivoted to an open position in the manner above described whereupon said coin will fall outwardly and downwardly, to be returned to the customer in the manner previously stated. In the event a subsequently inserted coin is used to increase the weight applied to the balancing means 126, with a view to causing rotation of the lever 129, the first underweight coin retained by the lug 130 will be wedged in the arcuate edge 45 on rib 44 as shown in Fig. 1. The wedging action of the first coin will prevent following coins from weighting the lever arm to cause rotation thereof.

If a slug or coin containing magnetic material is inserted into the coin passage 28, the coin or slug will roll down the passage until it reaches the lower end portion thereof where it will enter the magnetized zone created by the magnet 102 and the pins 103 and be arrested against the inner surface of the cover plate 70 by the magnetized pins 103, the magnet 102 being in contact with the outer ends of the pins as shown in Fig. 5. Upon operating the link 119, the pivoted outward movement of cover plate 70 will cause the pivoted magnet holder 95 to assume a position, with respect to cover plate 70, wherein the magnet 102 is separated from the pins 103, as shown in Fig. 6. The pins 103 will thereupon be demagnetized, causing the coin to drop from its position adjacent the inner face of the plate 70 downwardly outside the coin selector. The magnetic coin may be returned to the customer in the same manner as previously described.

It will be noted that the entry portion of coin passage 28 is defined by the rib 23 together with the vertical projecting edge 33 and the raised rib portion 42 which produces an offset in the passage. Coins inserted into the passage strike the projection 33 and the moving speed of said coins is thus reduced in order that all coins will ap-

proach the coin measuring opening 47 and the balancing means 126 at substantially a uniform speed, thus increasing the efficiency and accuracy with which improper coins will be arrested within the coin selector.

The genuineness of coins inserted into coin passages 29 and 30 is tested therein in a manner identical to that above described in connection with the coin passage 28. Slugs or coins containing magnetizable material inserted into the passage 29 will be arrested on the inner surface of the cover plate 85 due to the action of the magnet 102 mounted on the bracket portion 104 of the plate 70 and overlying the steel pins 103 in the plate 85. Upon pulling the link 119, the cover plates 70 and 85 will be pivoted outwardly to cause the magnet 102 on the bracket portion 104 of the plate 70 to separate from the pins 103 on the plate 85, as shown in Fig. 6, and the counterfeit coin or slug will then drop downwardly outside the coin selector to be recovered in the manner previously described. Similarly, a slug or the like of magnetic material inserted into the passage 30 will be arrested against cover plate 93 in the passage by means of the magnet 102 mounted on the bracket portion 104a of the plate 85, said magnet normally being in contact with the pins 103 mounted in the plate 93. The slug so arrested may be removed from its arrested position in a manner identical to that described above.

The foregoing description has been given for clearness or understanding only and no unnecessary limitations should be understood therefrom, but the appended claims should be construed as broadly as permissible in view of the prior art.

I claim:

1. A coin selector comprising: an inclined coin passage having an opening in a side thereof; a depression in said side adjacent said opening for entrapping an undersize coin; a coin gate enclosing a second side of said coin passage, said coin gate being movable to provide a second opening in said passage; a tilting plate normally disposed across said passage adjacent said depression for guiding undersize coins into said depression, said plate having a beveled edge adapted to be contacted by a proper coin whereby the plate may be moved to non-obstructing position by such a coin; and a finger movable through said first opening and into contact with said entrapped undersize coin for dislodging the latter from said depression and expelling the same from said passage through said second opening.

2. A coin selector comprising: an inclined coin passage having an opening in a side thereof; a depression in said side adjacent said opening for entrapping an undersize coin; a coin gate enclosing a second side of said coin passage, said coin gate being movable to provide a second opening in said passage; a light pivoted plate mounted on said coin gate opposite said depression and normally disposed across said passage for guiding undersize coins into said depression, said plate being movable by a proper coin to non-obstructing position; and a finger movable through said first opening and into contact with said entrapped undersize coin for dislodging the latter from said depression and expelling the same from said passage through said second opening.

3. A coin selector comprising: an inclined coin passage having an opening in a side thereof; a depression in said side adjacent said opening for entrapping an undersize coin; a coin gate enclosing a second side of said coin passage, said

11

coin gate being movable to provide a second opening in said passage; a finger movable through said first opening and into contact with said entrapped undersize coin for dislodging the latter from said depression and expelling the same from said passage through said second opening; and a guide member normally disposed across said passage for guiding undersize coins into said depression, said member being pivotally mounted upon said coin gate and having an end supported by said finger.

4. A coin selector comprising: an inclined coin passage having an opening in a side thereof; a depression in said side adjacent said opening within which an undersize coin may be entrapped; a coin gate enclosing a second side of said coin passage, said coin gate being movable to provide a second opening in said passage; an entry passage through which coins pass before entering said coin passage, said entry passage being offset relative to the coin passage; a surface projecting into the path of coins passing from said entry passage into said coin passage whereby the speed of rapidly moving coins will be reduced and all coins moving in said coin passage will approach said depression at substantially the same speed; and a finger movable through said first opening and into contact with an undersize coin entrapped in said depression for dislodging said coin from said depression and expelling the same from said coin passage through said second opening.

5. A coin selector comprising: an inclined coin passage having an opening in a side thereof; a depression in said side adjacent said opening within which an undersize coin may be entrapped; a coin gate enclosing a second side of said coin passage, said coin gate being movable to provide a second opening in said passage; an

12

entry passage through which coins pass before entering said coin passage, said entry passage being offset relative to the coin passage; a surface projecting into the path of coins passing from said entry passage into said coin passage whereby the speed of rapidly moving coins will be reduced and all coins moving in said coin passage will approach said depression at substantially the same speed; a movable guide member normally disposed across said coin passage adjacent said depression for guiding undersize coins into said depression; and a finger movable through said first opening and into contact with an undersize coin entrapped in said depression for dislodging said coin from said depression and expelling the same from said coin passage through said second opening.

LOUIS STEINER.
